US00D820688S

(12) **United States Design Patent** (10) **Patent No.:** **US D820,688 S**
Fath (45) **Date of Patent:** **** Jun. 19, 2018**

(54) **DISPLAY PACKAGE**

- (71) Applicant: **Altria Client Services LLC**,
Richmond, VA (US)
- (72) Inventor: **Scott A. Fath**, Richmond, VA (US)
- (73) Assignee: **ALTRIA CLIENT SERVICES LLC**,
Richmond, VA (US)
- (**) Term: **15 Years**
- (21) Appl. No.: **29/546,678**
- (22) Filed: **Nov. 24, 2015**

CLAIM

The ornamental design for a display package, as shown and described.

DESCRIPTION

FIG. 1 is a perspective view of a display package showing my new design.

FIG. 2 is a front elevational view thereof.

FIG. 3 is a rear elevational view thereof.

FIG. 4 is a right side elevational view thereof.

FIG. 5 is a left side elevational view thereof.

FIG. 6 is a top plan view thereof; and,

FIG. 7 is a bottom plan view thereof.

The portions of the display package shown in broken lines in FIGS. 1-7 represent unclaimed subject matter and form no part of the claimed design.

1 Claim, 7 Drawing Sheets
